UNITED STATES PATENT OFFICE.

MAURICE BABANI, OF PARIS, FRANCE.

DESIGN FOR A BOTTLE.

Application filed November 12, 1927. Serial No. 24,096. Term of patent 14 years.

To all whom it may concern:

Be it known that I, MAURICE BABANI, a citizen of the Republic of France, residing at Paris, Republic of France, have invented a new, original, and ornamental Design for a Bottle, of which the following is a specification, reference being had to the accompanying drawing, forming a part thereof.

In the drawing

Fig. 1 is a front view showing my improved bottle.

Fig. 2 is a side view.

Fig. 3 is a top plan view.

I claim:

The ornamental design for a bottle substantially as shown.

MAURICE BABANI.
